(57) **CLAIM**

The ornamental design for a tent as shown and described.

DESCRIPTION

FIG. 1 is a perspective view of a tent showing my new design;

FIG. 2 is a another perspective view thereof;

FIG. 3 is a rear elevational view thereof;

FIG. 4 is a front elevational view thereof;

FIG. 5 is a right side elevational view thereof;

FIG. 6 is a left side elevational view thereof;

FIG. 7 is a top plan view thereof; and,

FIG. 8 is a perspective view of the tent where the tent is in a configuration of use.

The portions shown in FIG. 8 illustrated using grey half tones and bound by a broken line illustrate environment only and form no part of the claimed design.
